UNITED STATES PATENT OFFICE.

EGBERT H. GOLD, OF CHICAGO, ILLINOIS.

CAR-HEATING SYSTEM.

Application filed July 27, 1923. Serial No. 654,229.

My invention relates to a steam heating system for railway cars in which the radiator consists of one or more pipe coils extending lengthwise of the car along the side 5 wall or walls thereof and preferably also partway along the ends of the car. The invention is concerned with certain improvements in the construction of a radiating coil of this type adapting it particularly for use 10 in a heating system, the circulation of medium through which is ultimately controlled by a thermostat subject to temperature changes in the car atmosphere; although the improved radiator might be employed in a hand regulated steam heating system either 15 of the vapor or high pressure type. A common form of radiating coil heretofore used in railway car heating systems consists of inlet and return pipes extending in opposite directions along the side wall of the car, from a controlling valve located at approximately the middle of the car, together with one or more, frequently two, intermediate 20 pipes connected with the extremities of the pipes connected with the extremities of the 25 inlet and return pipes by manifolds, the inlet, return and intermediate pipe or pipes having end sections standing at right angles to the main portions of the pipes. These end sections are connected to the main portions 30 of the pipes, respectively, by elbow joints and the extremities of all the end sections, at each end of the car, have been joined by a single manifold. The construction of the coil is such, therefore, that when 35 it is filled with steam, for example, with steam at atmospheric pressure in the case of a heating apparatus of the vapor type, the distribution of heat will be equal throughout the length of the radiator. That is to 40 say, the delivery of heat from the radiator is the same per linear unit throughout the length of the coil. The result is that the ends of the car, due to heat losses through the doors are likely to be cooler than the middle part. This condition is particularly 45 disadvantageous in a heating system in which the circulation through the radiator is ultimately controlled by a thermostat responsive to changes in temperature within the car. 50 In such case the thermostat is ordinarily located in the middle of the car and as a consequence it may act to shut off inflow of heating medium to the coil before the ends of the coil have been completely filled. With an 55 automatically operated system of this type the radiator valve is naturally opened and closed quite frequently, that is, as often as the temperature near the thermostat exceeds or falls below the temperature at which the thermostat is set for actuation. If conditions are such that the middle of the car heats up more rapidly than the ends (and such conditions are usual, particularly in severe weather) the radiator valve may be opened and closed at such short intervals 60 that the ends of the coil do not get a chance 65 to supply heat to their respective portions of the car at full capacity.

My invention provides a construction of the coil which increases the amount of the 70 radiating surface at the ends of the car and proportionately decreases the amount of radiating surface at the middle of the car. This I accomplish preferably by making the middle of the radiator a two-pipe coil, for 75 example, that is, consisting of two parallel pipes, and the end portions three-pipe coils, that is, consisting, in each case, of three parallel pipes. Obviously the number of pipes 80 might be increased.

The invention is illustrated, in a preferred embodiment, in the accompanying drawing wherein

Fig. 1 is a diagrammatic view illustrating a railway car heating system provided with 85 a radiator constructed in accordance with my invention, the radiator being shown, for the purpose of illustrating the object of the invention, not as it is actually constructed but in a schematic manner.

Fig. 2 is a fragmentary view, in perspective, of one end of the radiating coil showing the pipes and fittings in their actual arrangement.

Referring first to Fig. 1 of the drawing 95 which illustrates diagrammatically a steam heating system of the vapor type controlled by a thermostat located within the car: 10 designates the body of the car, 11 the steam train pipe, 12 a pressure reducer or vapor 100 regulator of common type, and 13 a valve for controlling the circulation of low pressure steam through the radiator which is here shown as consisting of two coils A and B arranged substantially as shown in United 105 States Patent No. 1,440,702 granted to Russell & Geissinger January 2, 1923, and in the patent to E. A. Russell No. 1,440,701 of the same date, which also illustrates the construction of the radiator valve 13 shown 110 herein. The coils A and B hereof, while bearing the same relation to each other as

the coils of the Russell & Geissinger and Russell patents, are of different and improved construction as will be hereinafter set forth.

5 14 is a pipe connecting the vapor regulator on its high pressure side with the train pipe 11. 15 is a pipe leading from the low pressure side of the vapor regulator to valve 13. 16 is a pipe for conducting water of 10 condensation from valve 13 to the thermostat chamber of the vapor regulator. The vapor regulator operates, it will be understood, to prevent the introduction into the radiator of steam in excess of that which can be 15 condensed therein and controls the system to that extent. Ultimate control, however, is dependent upon a thermostatic device 17, preferably located near the middle of the car adjacent one side wall, which actuates 20 certain apparatus to close and open the radiator valve 13 on rise and fall of the temperature in the car. The apparatus actuated by the thermostat may be that shown in the Russell Patent 1,440,701 above 25 mentioned, and as it forms no part of my present invention it has been shown only fragmentarily. The valve body of valve 13 is rotated to closing position, and vice versa, by a lever 18 moved in opposite directions 30 by solenoids 19 and 20 energized through the operation of thermostat 17.

In the arrangement of the coils shown steam passes into coil A through pipe 21 and then after circulating through this coil 35 enters coil B through pipe 22, the water of condensation from coil A being discharged through train pipe 23 and the valve 13. The medium from coil B enters valve 13 through pipe 24.

40 Both of the coils A and B are illustrated in Fig. 1 as of substantially the same construction. That is, each coil is so constructed that the end portions thereof have more radiating surface per linear movement 45 than the middle portion. Under some circumstances it might be sufficient to construct only one of the coils in this manner.

To take coil A as an example: It consists of an inlet pipe 25 which runs the 50 length of the car from its connection with the valve 13 at the middle of the car, and is provided with an end section 26, pipe sections 25 and 26 being at right angles to each other and connected by an elbow 27. 28 is 55 a return pipe extending from the other end of the car to the valve 13 and connected therewith through pipes 22 and 23. The return pipe is also shown as provided with an angularly disposed end section 29, sections 28 and 29 being connected by elbow 27. 60 Connecting opposite ends of the inlet and return pipes, is an intermediate pipe consisting of a longitudinal pipe section 30 extending the entire length of the car and provided at opposite ends with end sections 31

and 32, which are connected to sections 30 by elbows 27. At the opposite ends of the coil are additional pipes 33, 34 paralleling the inlet return and intermediate pipes and provided preferably with end sections 35, 36 connected thereto by elbows 27. The additional pipes 33, 35 and 34, 36 are connected with the intermediate pipe 31, 32 by Y fittings 37. The intermediate pipe is connected at opposite ends with the extremities of the 75 inlet and return pipes, respectively, by return bend fittings 38.

With the coil constructed as above set forth, the delivery of heat therefrom per linear unit will be greater at the ends of the 80 coil in the ratio of three to two than at the middle portion of the coil.

Fig. 1, for the purpose of clearly illustrating the invention, shows the pipes as though they were in the same horizontal plane. 85 The actual construction of the coil is illustrated in Fig. 2 in which the parallel pipes are shown as arranged one above the other.

While the invention has been shown and described in the preferred embodiment, it is 90 my intention to cover all modifications of the same within the scope of the appended claims.

I claim:

1. In combination with a railway car, a 95 heating system therefor, having a radiating coil consisting of inlet and return pipes extending from a middle point in the car toward opposite ends thereof, an intermediate pipe connecting the outer ends of the 100 inlet and return pipes, and additional pipes paralleling and connected with said last named pipe at the ends thereof.

2. In combination with a railway car, a 105 heating system therefor having a radiating coil consisting of inlet and return pipes extending from a middle point in the car toward opposite ends thereof, an intermediate pipe extending between the outer extremities of the inlet and return pipes, return 110 bend fittings connecting said intermediate pipe with the extremities of the inlet and return pipes, respectively, an additional pipe paralleling the intermediate pipe at one end thereof, and Y fittings connecting said additional pipe with the intermediate pipe. 115

3. In combination with a railway car, a 120 radiator extending lengthwise of the car and mechanism for controlling the circulation of heating medium through the radiator comprising a thermostat subject to changes of temperature in the car atmosphere and located near the middle of the car, the end portions of said radiator having more radiating surface per linear unit than the mid- 125 dle portion, for the purpose specified.

4. In combination with a railway car, a 130 radiator comprising parallel pipes extending lengthwise of the car, and mechanism for controlling the circulation of heating

medium through the radiator comprising a 5 thermostat subject to changes of temperature in the car atmosphere and located near the middle portion of the car, the end portions of said radiator consisting of a larger number of parallel pipes than the middle portion thereof.

5. In combination with a railway car, a steam train pipe, a radiating coil, and a 10 valve arranged near the middle of the car for controlling the inflow of steam from the train pipe to the coil and the discharge of water of condensation from the coil; said coil comprising inlet and return pipes connected with said valve and extending to the 15 ends of the car and provided with angularly disposed end sections, an intermediate pipe extending the length of the car and provided with angularly disposed end sections,

fittings by means of which the end sections 20 of said inlet, return and intermediate pipes are connected, additional pipes at the ends of the coil having angularly disposed end sections, and Y fittings by means of which said additional pipes and said intermediate 25 pipe are connected.

6. A railway car radiating pipe coil having two parallel pipes comprising, in each case, pipe sections at an angle to each other, a third pipe comprising angularly disposed 30 sections parallel to the sections of the other pipes respectively, Y fittings for connecting said third pipe to one of the first mentioned pipes and a fitting by means of which the extremities of said first mentioned pipes are 35 connected.

EGBERT H. GOLD.
